DESIGN FOR A SERVICE BILL BLANK

Ashton B. Collins, Birmingham, Ala.

Application March 30, 1939, Serial No. 83,925

Term of patent 14 years

To all whom it may concern:

Be it known that I, Ashton B. Collins, a citizen of the United States, residing at Birmingham, in the county of Jefferson and State of Alabama, have invented a new, original, and ornamental Design for a Service Bill Blank, of which the following is a specification, reference being had to the accompanying drawing, forming part thereof.

The figure is a plan view of a service bill blank showing my new design.

I claim:

The ornamental design for a service bill blank, as shown.

ASHTON B. COLLINS.
